UNITED STATES PATENT OFFICE

CHARLES F. WRIGHT, OF AKRON, OHIO, ASSIGNOR TO THE DIAMOND MATCH COMPANY, OF BALTIMORE, MARYLAND, A CORPORATION OF MARYLAND

MECHANISM FOR STACKING PACKAGES

Application filed August 25, 1931. Serial No. 559,164.

The object of this invention is to provide a machine of simple and efficient construction and operation for stacking and arranging packages of matches or other articles in an orderly manner whereby predetermined numbers of the assembled packages can be readily selected and removed for subsequent operations, which machine is especially, though not exclusively, designed for use in connection with or as an attachment for a machine from which wrapped packages are successively delivered.

With this object in view my invention embodies features of novelty and combinations of parts which in a preferred form will be hereinafter described; the scope of the invention then being expressed in the following claims.

In the drawings—

20 Fig. 1 is a side elevation of a machine embodying my invention, showing the package lifter arms in raised position at the completion of a package stacking operation.

25 Fig. 2 is a partial plan, enlarged, of the machine, the lifter arms being shown in down or package receiving position.

Fig. 3 is a transverse vertical section in a plane through the forward ends of the lifter arms, as on the line 3—3 of Fig. 2.

30 Fig. 4 is a similar section, as on the line 4—4 of Fig. 2, showing the conveyer, the drive mechanism therefor, and adjuncts.

Fig. 5 is a longitudinal vertical section of the machine, as on the line 5—5 of Fig. 2.

35 Fig. 6 is a view similar to Fig. 5 of a portion of the receiving end of the stacking table, the lifter arms and switch control devices therefor, together with stop devices for advancing packages, the said parts being shown in their respective positions during the initial upward movement of the lifter arms.

Fig. 7 is a longitudinal vertical section 45 of a lifter actuating cam and clutch mechanism therefor, as on the line 7—7 of Fig. 2.

Fig. 8 is a transverse vertical section, as on the line 8—8 of Fig. 7.

Fig. 9 is a section through the switch and 50 its support.

Fig. 10 is a transverse section through the switch, as on the line 10—10 of Fig. 9.

Referring to the drawings, 15 designates a frame structure upon which is supported a horizontal bed or table 16 having at its receiving end a downwardly curved portion 17 which overhangs the delivery end of the upper horizontal run of an endless belt conveyer 18. This conveyer is supported and guided by pulleys 19, 20, whereof the shafts 21 have their bearings in suitably-disposed brackets 22 on the frame structure. The upper run of the conveyer is also guided and sustained by a longitudinally extending bed 23 which is supported by bridge members 24 on the frame structure. The shaft 21 of the pulley 20 at the delivery end of the conveyer has fast thereon a sprocket 25 which is connected by a chain 26 with a sprocket 27 fast on a shaft 28 having its bearings in standards 29. The latter shaft is driven from a suitable source of power, and hence the motion is transmitted by the sprocket gearing to the shaft 21 of the pulley 20 in a manner to impel the conveyer continuously in the direction indicated by the adjacent arrow. (Fig. 5.) In the present instance the shaft 28 is operatively connected through suitable sprocket and chain gearing 30 with an electric motor 31.

The packages (P) to be assembled are successively placed upon the upper run of the conveyer 18 and are carried thereby in more or less close relation toward the curved portion 17 of the table 16. Preferably the conveyer is arranged to receive the packages as they are discharged from a wrapping machine of any usual or approved construction, a dryer trunk as 32, being interposed between the wrapping machine and the conveyer in order to ensure the drying of the adhesive on the wrappers before the packages pass to the conveyer.

The width of the conveyer 18 is less than the length of the packages imposed thereon, so that the ends of the packages project beyond the respective longitudinal edges of the belt.

Parallel guide rails 33 for the row of packages on the conveyer are supported adjacent

the respective sides of the conveyer by means of suitably-disposed brackets 34, and means, such as a continuously driven feed wheel 35, for advancing each succeeding package at the receiving end of the conveyor is preferably provided, which wheel frictionally contacts with the tops of the adjacent boxes. The shaft 36 of this wheel has its bearings in brackets 37 on the guide rails and has fast thereon a sheave 38 which is connected by a belt 39 with a sheave 40 fast on the shaft of the pulley 20 at the delivery end of the conveyer.

A shoe 41 extends above the row of packages and insures their orderly arrangement on the conveyer as they approach the curved end of the table, which shoe is supported by a bridge bracket 42 secured to the respective guide rails.

Extending adjacent the respective sides of the delivery end of the conveyer and forwardly of the curved end portion of the table are a pair of lifter arms 43 which are connected by a sleeve 44 loose on a cross-shaft 45 that is fixed in suitably-disposed brackets 46 on the supporting structure. These lifter arms when they are in horizontal position extend sufficiently inward to underlie and receive the ends of a definite number (in the present instance, three) of close-lying leading packages on the conveyer adjacent the curved end of the table. The sleeve 44 is provided with a crank arm 47 which is connected by means of a link 48 with the longer arm 49 of a lever 50 fulcrumed on a cross-shaft 50 that is fixed in suitably-located brackets 51 on the frame structure. The other arm 52 of the lever carries a roll 53 in contact with a suitable cam 54 on a cross-shaft 55 having its bearings in brackets 56 on the frame structure. This shaft 55 has fast thereon a sprocket 57 which is connected by means of a chain 58 with a sprocket 59 on the driven shaft 28. The roll 53 is maintained yieldably in contact with the cam 54 by means of a spring 60 which connects the longer lever arm 49 with a suitably-disposed fixture 61, and the cam is automatically fixed to and released at intervals from the shaft 55 by means under the control of the advancing packages on the conveyer as will be hereinafter described.

The contour of the cam 54 is such that when it is secured to and rotated by the shaft 55 the lever arm 49 is alternately raised and lowered by the co-action of the cam and the spring 60, thereby effecting through the crank and link connections 47, 48 the upward and downward swinging of the lifter arms 43 through an arc of 90°. These arms in their upward travel raise the three opposing packages along the curved portion 17 of the table and by virtue of the partial turning of the packages as they bear upon and slide along such curved portion the packages are arranged in upright or stacked condition on the

table. When such packages are thus arranged on the table the lifter arms 43 are immediately swung downward to their previous position below the path of the next succeeding series of packages borne by the conveyer, preparatory to another stacking operation, and so on. As each stack of packages is delivered to the table the preceding stack or stacks are successively advanced along the table, thus ensuring a row of close-lying uniformly stacked packages from which predetermined numbers of stacks can be readily removed for wrapping or other purposes.

The preferred means for automatically clutching and releasing the cam 54 on the shaft 55 is as follows: The cam has a hub 62 formed with end heads 63, 64, which hub is loosely mounted on the shaft 55 between the sprocket 57 and a collar 65 fast on the shaft. The end heads 63, 64 are faced with friction material 66 in contact with disks 68, 69 on the opposing faces of the sprocket hub and the collar. The disk 69 is fast on the collar, and the disk 68 is slidably secured to the sprocket hub by pins 690. The disk 68 is pressed yieldably against the opposing friction material of the cam head 63 by springs 70 seated in sockets 71 in the sprocket hub. These springs exert sufficient force to clutch the cam 54 to the shaft 55 by the opposing friction surfaces, thus, if the cam can be unrestrained, ensuring its rotation to effect the vibratory operation of the lever 49, 52 and its appurtenances.

The cam 54 when the lifter arms are in down or horizontal position is restrained against rotation with the shaft 55 by means of a depending dog 71 in engagement with a tooth or shoulder 72 on the end head 63 of the cam hub, which dog is conveniently pivoted on a suitably-disposed bracket 74. The dog is pivotally connected, as at 75, with the core of a solenoid 76, the coil of which latter is included in an electric circuit 77 which may be alternately made and broken by a suitable switch 78 under the control of the predetermined leading packages on the conveyer.

In the present instance a mercury switch is employed, which switch is carried by supporting brackets 79 carried by one of two spaced upstanding arms 83, each of which is adjustably secured by means of a screw 80 to a rock-shaft 81 having its bearings in brackets 82 on the frame structure directly below the path of the leading packages on the conveyer. The upper ends of these arms project above the respective sides of the upper run of the conveyer into the path of the leading package as it approaches the table. One of the arms 83 is provided with a crank-arm 84 from which are suspended adjustable weights 85 which tend to swing the arms forwardly of the table and with their upper ends in the path of the leading package. These weights are so adjusted that there must

be at least a definite number of packages on the conveyer to cause sufficient retarding friction on the packages to enable them to push back the arms 83 against the force of the counterweights. In the present instance 5 three or more packages are required for this purpose. When the leading three packages are located above the lifter arms 43 the switch control arms 83 are swung to their backward 10 limit, in which case the mercury element of the switch connects the terminals as indicated in Fig. 9 and completes the electric circuit 77, thus the solenoid is energized and the retraction of its core is effected. This 15 retracts the pendant dog 71 from the tooth of the head 63 on the cam hub, thus releasing the cam 54 and ensuring its rotation concurrently with the shaft 55.

In order to prevent the advancement of the 20 succeeding packages on the continuously moving conveyer 18, during the rise and fall of the lifter arms 43, suitable stop means operating in timed relation to the arms 43 is provided, as follows:

25 86 designates a pair of horizontally-disposed arms arranged at the respective sides of the conveyer and secured at their forward ends to a rock-shaft 87 having its bearings in brackets 88 on the supporting structure. 30 The rear or free ends of these arms 86 are yieldingly held in raised position by means of a spring 89 one end of which is secured to a depending arm 90 on the shaft 87, and the other end is secured to the bridge bracket 35 24 supporting the longitudinal bed 23. The ends of the arms 86 are formed with lateral projections 92 which underlie the free ends of the lifter arms 43 and are depressed by the latter against the action of the spring 40 89 when the lifter arms are in down or package receiving position. The projections 92 have secured thereto upstanding stop members 93 which, when the arms 86 are depressed, lie below the path of the packages 45 borne by the conveyer, but on the initial upward movement of the lifter arms the arms 86 move slightly upward to project the stop members into the path of the opposing progressing packages, thus temporarily preventing 50 the advancement of the latter, as previously mentioned. The stop members 93 are maintained in raised or active position until the succeeding descent of the lifter arms, whereupon such members are again depressed below the path of the packages on 55 the carrier to enable another series to advance upon the lifter arms, and so on. The free ends of the arms 86 have secured thereto 60 upstanding side plates 94 which, abutting against the under sides of the opposing guide rails 33, limit the upward movement of the arms 86.

My invention is not limited to the particular exemplifying form of embodiment herein disclosed, as the construction may be modi-

fied within the principle of the invention and the scope of the appended claims.

I claim—

1. In combination with a package support, means on a lower level for advancing a succession of packages toward said support, lifter arms which normally underlie the path of a leading series of packages, means including a cam for actuating said lifter arms to raise the opposing packages and position them in stacked relation on the support, an intermittently-acting stop device for said cam, an electric circuit in which are included an electro-magnet for controlling the stop device and a switch for making and breaking the circuit, and means extending into the path of the leading advancing package for controlling the operation of the switch. 70

2. In combination with a package support, means on a lower level for advancing a succession of packages toward said support, lifter arms which normally underlie the path of a leading series of packages, means including a cam for actuating said lifter arms to raise the opposing packages and position them in stacked relation on the support, an intermittently-acting stop device for said cam, an electric circuit in which are included an electro-magnet for controlling the stop device and a switch for making and breaking the circuit, and means for controlling the operation of the switch including rocker-arms which extend into the path of the leading advancing package. 80

3. In combination with a package support, means on a lower level for advancing a succession of packages toward said support, lifter arms which normally underlie the path of a leading series of packages, means including a cam for actuating said lifter arms to raise the opposing packages and position them in stacked relation on the support, an intermittently-acting stop device for said cam, an electric circuit in which are included an electro-magnet for controlling the stop device and a switch for making and breaking the circuit, means for controlling the operation of the switch including rocker-arms which extend into the path of the leading advancing package, and an adjustable counterpoise for said switch and rocker-arms. 105

4. In combination with a package support comprising a table having a downwardly curved receiving portion, a conveyer on a lower level for advancing a succession of packages toward said receiving portion, oscillatory lifter arms which normally underlie the path of a leading series of packages adjacent said receiving portion and are operative to move such series along the receiving portion and position them in stacked relation on the table, means including a rotary cam for actuating said lifter arms, an intermittently-acting stop device for said cam, an electric circuit in which are included an electro-mag- 110 120 125 130

- net for controlling the stop device and a switch for making and breaking the circuit, and means extending into the path of the leading advancing package on the conveyer for controlling the operation of the switch.
5. In combination with a package support comprising a table having a downwardly curved receiving portion, a conveyer on a lower level for advancing a succession of packages toward said receiving portion, oscillatory lifter arms which normally underlie the path of a leading series of packages adjacent said receiving portion and position them in stacked relation on the table, means including a rotary cam for actuating said lifter arms, an intermittently-acting stop device for said cam, an electric circuit in which are included an electro-magnet for controlling the stop device and a switch for making and breaking the circuit, and means for controlling the operation of the switch including rocker-arms which extend into the path of the leading advancing package.
6. In combination with a package support comprising a table having a downwardly curved receiving portion, a conveyer on a lower level for advancing a succession of packages toward said receiving portion, oscillatory lifter arms which normally underlie the path of a leading series of packages adjacent said receiving portion and position them in stacked relation on the table, means including a rotary cam for actuating said lifter arms, an intermittently-acting stop device for said cam, an electric circuit in which are included an electro-magnet for controlling the stop device and a switch for making and breaking the circuit, means for controlling the operation of the switch including rocker-arms which extend into the path of the leading advancing package, and an adjustable counterpoise for said switch and rocker-arms.
7. In combination with a package support comprising a table having a downwardly curved receiving portion, a conveyer on a lower level for advancing a succession of packages toward said receiving portion, oscillatory lifter arms which normally underlie the path of a leading series of packages adjacent said receiving portion and position them in stacked relation on the table, means including a rotary cam for actuating said lifter arms, an intermittently-acting stop device for said cam, an electric circuit in which are included an electro-magnet for controlling the stop device and a switch for making and breaking the circuit, means for controlling the operation of the switch including rocker-arms which extend into the path of the leading advancing package, an adjustable counterpoise for said switch and rocker-arms, and stop means for the advancing packages on the conveyer including vibratory arms extending into the path of the lifter arms.
8. In combination with a package support, means for advancing a succession of packages toward said support, transfer means normally adjacent the path of a leading series of packages, means including a cam for actuating said transfer means to transfer the opposing packages to the support, an intermittently-acting stop device for said cam, an electric circuit in which are included an electro-magnet for controlling the stop device and a switch for making and breaking the circuit, and means extending into the path of the leading advancing package for controlling the operation of the switch.
9. In combination with a package support, means for advancing a succession of packages toward said support, transfer means normally adjacent the path of a leading series of packages, means including a cam for actuating said transfer means to transfer the opposing packages to the support, an intermittently-acting stop device for said cam, an electric circuit in which are included an electro-magnet for controlling the stop device and a switch for making and breaking the circuit, means extending into the path of the leading advancing package for controlling the operation of the switch, and means for arresting the advancing packages rearward of the transfer means during each operation of said transfer means.
10. In combination with a package support, means for advancing a succession of packages toward said support, transfer means normally adjacent the path of a leading series of packages, and electrically-controlled means for operating said transfer means in timed relation to the travel of the advancing packages, said electrically-controlled means including an electric circuit having a switch for making and breaking said circuit, and a rocker arm carrying said switch and extending into the path of the leading advancing package.
11. In combination with a package support, means for advancing a succession of packages toward said support, transfer means normally adjacent the path of a leading series of packages, and electrically-controlled means for operating said transfer means in timed relation to the travel of the advancing packages, said electrically-controlled means including an electric circuit having a switch for making and breaking said circuit, a rocker arm carrying said switch and extending into the path of the leading advancing package, and an adjustable counterpoise for said rocker arm and switch.

Signed at Barberton in the county of Summit and State of Ohio this 18th day of August A. D. 1931.

CHARLES F. WRIGHT.
